CLOTHES HANGER

John T. Dolan, New Rochelle, N. Y.

Application October 3, 1946, Serial No. 700,873

3 Claims. (Cl. 211—89)

1

This invention relates to new and useful improvements and structural refinements in clothes hangers, and the principal object of the invention is to provide a device of the character herein described, such as may be conveniently and effectively employed for supporting clothes while drying.

A further object of the invention is to provide a clothes hanger which is particularly adapted for attachment to a suitable supporting structure, such as a wall of a building, and which is of a collapsible nature, whereby the same may be easily folded when not in use.

Another object of the invention is to provide a clothes dryer which is simple in construction, pleasing in appearance, and which may be easily manipulated.

An additional object of the invention is to provide a clothes dryer which will readily lend itself to economical manufacture and which will not easily become damaged.

With the above more important objects in view, and such other objects as may become apparent as this specification proceeds, the invention consists essentially of the arrangement and construction of parts as illustrated in the accompanying drawings, in which:

Figure 1 is a front elevation of the invention.

Figure 2 is a side elevation thereof.

Figure 3 is a top plan view of the same, and

Figure 4 is a fragmentary detail showing the mounting of clothes pins used in the invention.

Like characters of reference are used to designate like parts in the specification and throughout the several views.

Referring now to the accompanying drawings in detail, the invention consists of a clothes hanger designated generally by the reference character 10, the same embodying in its construction a pair of spaced upright side members 11 secured together by upper and lower cross members 12 and 13 respectively, and coacting therewith to form what may be referred to as a stationary framework 14.

If desired, the cross members 12, 13 may be of a rod-like configuration, and it will be noted that the side members 11 are provided at the upper ends thereof with a pair of suspension brackets 15, whereby the hanger as a whole may be conveniently suspended or attached to suitable supporting structure, such as the wall 16 of a building.

A movable rack 17 consists of a pair of spaced side bars 18, each of the latter, in turn, comprising a pair of spaced side pieces 19. A pair of trans-

versely extending tie rods 20 and 21 are disposed adjacent the opposite end portions of the side bars 18, whereby the set of four side pieces (19) is rigidly secured together, as will be clearly apparent from the accompanying drawings.

The tie rod 21 is somewhat longer with respect to the rod 20 and the end portions thereof are rotatably journalled in the lower end portions of the side members 11, whereby the rack 17 may be swung, so to speak, as indicated at 22.

Means are provided for retaining the rack 17 in a substantially horizontal position, the same comprising a pair of flexible suspending members, such as the chains 23, attached at one end to the cross member 12 and at the remaining end to the tie rod 20.

A row of clothes pins 24 of conventional design is provided between the side pieces 19 of each of the side bars 18, said pins being transversely aligned in pairs, in order that each pair of pins may be conveniently employed for supporting an article of laundry.

Each of the clothes pins 24 is pivotally attached, so to speak, to the adjacent side pieces 19 by means of a short shaft or pin 25, so that the pins will be disposed in a substantially upright position, when the rack 17 is substantially horizontal, as is best shown in Figure 2.

When the invention is not in use, the rack 17 may be simply swung into its folded or collapsed position indicated by the phantom lines 26, during which action the clothes pins 24 will become nested, as it were, one upon another, as indicated in Figure 4.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A clothes hanger comprising in combination, a pair of spaced upright side members and upper and lower cross members connecting said side members and forming a stationary framework, said framework being adapted for attachment to supporting structure, a movable rack comprising a pair of spaced side bars and a plurality of transversely extending tie rods

securing said bars together, each of said bars comprising a pair of spaced side pieces, one of said tie rods being disposed adjacent one end of said rack and being rotatably journaled in the lower end portions of said side members, a pair of flexible suspending members extending between the remaining end of said rack and the upper end of said framework, and a row of clothes pins pivotally mounted between the side pieces of each of said side bars, said pins being transversely aligned in pairs.

2. A clothes hanger comprising a pair of parallel spaced members, means connecting said members to each other, a first and a second set of parallel side bars, a pivot shaft extending through one end of said first and second sets of said bars and through the lower ends of said members, a plurality of spaced pins extending through said side bars of each of said sets, a plurality of clothes pins disposed between said side bars of each set and pivotally mounted on said pins for movement between said side bars, and means including a flexible element attached to said first and second sets of side bars and to said members for supporting said side bars in a position disposed transversely of said members.

3. A clothes hanger comprising a pair of parallel spaced members, means connecting said mem-

bers to each other, a first and a second set of parallel side bars, a pivot shaft extending through one end of said first and second sets of said bars and through the lower ends of said members, a plurality of spaced pins extending through said side bars of each of said sets, a plurality of clothes pins disposed between said side bars of each set and pivotally mounted on said pins for movement between said side bars, a tie rod extending through and connecting the other ends of said first and second sets of side bars, a pair of flexible elements each having one end thereof secured to said tie rod adjacent one of said sets of side bars, the other ends of said elements being secured to said parallel members.
